MOVING ADVERTISING SIGN DISPLAY FOR STORES

John J. Casparro, Canoga Park, Calif., assignor to Don Fedderson Productions, Inc., Studio City, Calif.

Filed July 10, 1975, Ser. No. 594,780

Term of patent 14 years

Int. Cl. D20—03

U.S. Cl. D96—12 R

FIG. 1 is a front perspective view of a moving advertising sign display for stores embodying my new design;

FIG. 2 is a rear elevational view thereof;

FIG. 3 is a side elevational view thereof, as viewed from the left side of FIG. 1; and

FIG. 4 is a bottom plan view thereof.

I claim:

The ornamental design for a moving advertising sign display for stores, substantially as shown and described.
